UNITED STATES PATENT OFFICE.

WALTER D. BUTZ, OF NORRISTOWN, PENNSYLVANIA, ASSIGNOR OF ONE-HALF TO
LOUIS N. D. WILLIAMS, OF OGONTZ, PENNSYLVANIA.

STITCH-TRANSFERRING DEVICE.

1,068,853.

Specification of Letters Patent.

Patented July 29, 1913.

Application filed January 11, 1910, Serial No. 537,578. Renewed July 6, 1912. Serial No. 708,063.

To all whom it may concern:

Be it known that I, WALTER D. BUTZ, a citizen of the United States, residing in Norristown, Pennsylvania, have invented 5 certain Improvements in Stitch-Transferring Devices, of which the following is a specification.

The object of my invention is to provide means whereby the stitches may, with very 10 little labor or loss of time, be transferred from the needles of one knitting machine to those of another, or from the needles of a knitting machine to the "points" of a looping machine, the device also providing 15 means whereby the stitches throughout part of a course in a knitted web may be doubled with the stitches throughout the remaining portion of said course, in order that the doubled stitches may be united, or, as it is 20 usually termed, "looped," by means of a course of stitches engaging the same, as in closing the toe pocket formed upon the foot portion of a stocking, the device, in its preferred form, being susceptible of receiving 25 the stitches of the last course of a tubular web directly from the needles of a circular knitting machine upon which said tubular web has been knitted, then folding one-half of said tubular web back upon the other 30 half, doubling the stitches around the half course in said folded portion with those around the half course in the other portion and applying these doubled stitches to the 35 points of the looping machine, whereby they may be united.

In the accompanying drawings—Figure 1 is a vertical sectional view of a device constructed in accordance with my invention, and adapted for use in connection 40 with tubular webs, the parts being shown in the position which they assume when receiving the stitches from the needles of the machine upon which the web was knitted; Fig. 2 is a similar section illustrating the relation of the parts in respect to one another when the doubling of the 45 stitches around one-half of the tubular web with those around the other half of the same is to be effected; Fig. 3 is a face view of part 50 of the device; Fig. 4 is a horizontal section,

partly on the line *a—a*, and partly on line *b—b*, Fig. 3; Fig. 5 is a vertical section on the line *c—c*, Fig. 3, and Fig. 6 is a view of a stitch-receiving member designed for use in connection with a fine gage machine. 55

The device shown in the drawing, comprises a ring 1, recessed, as at 2, for the reception of a pair of semi-circular ring segments 3 and 3^a, the ring segment 3 being secured to the ring 1, as by one or more screws 4, but the ring segment 3^a being confined to said ring 1 by means of a spring-actuated latch 4^a, or equivalent device, whereby it may be disconnected from said ring 1, when such release is desired. The ring 1 60 is further recessed, as at 5, for the reception of various instrumentalities carried by the ring segments 3 and 3^a. As these instrumentalities are substantially the same upon each of said segments, a detailed description 65 of those of one segment only will suffice, and I will therefore describe the parts carried by the ring segment 3, the corresponding parts of the ring segment 3^a being indicated by the same reference numerals with 70 the addition of the letter "a."

Within the segment 3 is a segment composed of upper and lower members 6 and 7 secured together and to the segment 3 by means of one or more screws 9, or equivalent 80 fastenings, the lower segment 7 being slotted for the reception and guidance of a plurality of fingers, pins, points, needles or equivalent stitch-receiving members 10 which, for convenience, I have termed 85 "quills" this being the term commonly applied to the corresponding members of an ordinary stitch transfer head or ring. The quills 10 are pivoted at their upper ends, as at 11, and normally drawn inward or toward the center of the segment by means of a coiled spring 12 contained in a groove 13 formed in the segment 7. Each of the quills 10 is hollow or U-shaped in its upper portion for the reception of the upper portion 90 of a needle of the knitting machine, as shown by dotted lines in Fig. 1, but the quill terminates at its lower end in a thin and relatively elastic finger 14 which can fit snugly against the back of the needle and 100

pass between the same and the stitch carried by the needle.

Upon each of the quills 10 is formed a lug 15, beveled on its inner face, and these lugs 5 engage with the beveled outer face of a rib 16, formed around the lower portion of a segment 17, which is slotted, as at 19, for the reception of one or more screws 20, whereby it is secured to the segment 7 so as to be susceptible of a slight amount of vertical motion thereon, whereby its beveled rib 16 may, as shown in Fig. 1, act upon the beveled lugs 15 of the quills 10 to thrust the latter outwardly, or, by raising the segment 17, the 10 lugs 15 may be freed from the pressure of the rib 16 and the quills 10 therefore permitted to swing inwardly under the action of the spring 12. By reason of this construction the quills may receive stitches from the 15 needles of a knitting machine of one diameter and transfer said stitches to the needles of a knitting machine of another diameter, or to the points of a looping machine of a different diameter from that of the machine 20 upon which a knitted web has been produced. Vertical movements are imparted to the segment 17 by means of a segment 21 mounted upon the top of the segment 7 and having one or more cam slots 22 therein (see 25 dotted lines Fig. 1) for the reception of one or more pins 23 on the segment 17.

Inside of the segment 17, and between the same and the lower portion of the ring 1, is a segment 24, terminating at its lower end in 30 an outwardly projecting flange 25, slotted so as to form ribs or fingers 26 which project between the quills 10. The segment 24 is confined to the lower portion of the ring 1 by means of a screw 27 which is adapted to 35 a vertical slot 29 in the ring 1, as shown in Fig. 1, and is provided with an enlarged head 30 on the inner side of the ring so that the segment 24 and its slotted flange 25 can be readily raised and lowered by hand. 40 Preferably, the segment 24^a carried by the ring segment 3^a is provided with a slot 29^a and is guided upon the head of the screw 20^a, whereby the segment 17^a is confined to the segment 7^a, the segment 24^a being thus free 45 from any connection with the lower portion 50 of the ring 1.

The cam segment 21 can be operated in any available way so as to raise and lower the segment 17. In the present instance, I 55 have shown said cam segment as provided with a tongue 31 projecting through a slot 32 in the recessed or shouldered portion 5 of the ring 1.

The ring segments 3 and 3^a are pivoted together at each side of the ring 1 by means 60 such as shown in Figs. 3 and 4, the latter illustrating the pivotal means for the ring segments at one side of the ring 1, and the pivotal means at the opposite side of said 65 ring being precisely the same. The members

of the pivotal device are the same for each segment, hence I will describe only the members used in connection with the segment 3, those used in connection with the segment 3^a bearing corresponding reference numbers 70 to which have been added the distinguishing letter "a."

In the face of the ring segment 3, adjacent to the edge of the same, is formed a dovetailed groove 33, to which is adapted a dovetailed tongue 34 upon a slide 35, the latter having, at its lower end, a hinge member 36 similar to that of an ordinary rule joint, the hinge members of the cooperating slides being coupled by means of an axial pin or stud 80 37, as shown in Fig. 3.

The slide 35 can be supported in two different vertical positions upon the ring segment 3, the latter having vertically spaced notches 39 and 40, as shown in Fig. 5, and the slide 35 carrying a spring-actuated pin 41 with enlarged head, whereby it may be readily manipulated, this pin engaging the upper notch 39 when the slide 35 is in its raised position and engaging the lower notch 40 when the slide is in its lowered position, and, in either case, locking the slide in the position to which it had been adjusted. When the slide is in the elevated position, the pivot joint is above and out of the way 95 of the quills 10 so that it does not interfere with the proper application of the latter to the needles of the knitting machine, but, when the slide is in its lowered position, the axis of the hinge joint is in line with the 100 points of the quills and midway between an end quill of one ring segment and an end quill of the opposite ring segment, as shown by dotted lines in Fig. 3.

Mounted upon the slide 35 are a pair of 105 spring hooks 42 whose lower ends are in line horizontally with the axis of the hinge pin or stud 37, the normal position of these spring hooks being the retracted position shown by full lines in Fig. 5, that is to say 110 with the points of the hooks some distance outwardly beyond the quills 10. When, however, the slide 35 is lowered, the hooks 42 may be thrust inward by depressing a slide 43 mounted upon the slide 35 so as to be 115 movable vertically thereon, said mounting being effected, in the present instance, by adapting inwardly projecting ribs or flanges on the ends of the slide to corresponding grooves in the opposite sides of the slide 35. 120 By preference, one of the spring hooks 42 is bent at its lower end so that it can pass through the center of the pivot pin or stud 37 of the hinge, as shown in Fig. 3.

In the operation of the device the ring 125 segments 3 and 3^a are first adjusted in respect to the carrying ring 1, as shown in Fig. 1, and the cam segments 21 and 21^a are adjusted so as to raise the segments 17 and 17^a and thereby relieve the quills 10 and 10^a 130

from the outward thrust of the cam ribs 16 and 16^a of said segments, the quills being drawn inward by reason of the springs 12 and 12^a. The quills are then applied to the 5 raised needles of the knitting machine and the segments 17 and 17^a are depressed so as to thrust the fingers 14 and 14^a at the lower ends of the quills firmly against the backs of the needles, the ring 1 being then depressed 10 so that the points of the said fingers will project below the top of the needle cylinder whereby, when the needles are retracted, they will cast their stitches onto the fingers 14 and 14^a of the quills. The knitted web is 15 then drawn up through the interior of the ring 1 and the latter is removed from the knitting machine, the end course of stitches of the web now hanging upon the quills. These operations are performed while the 20 hinge slides 35 and 35^a are in the elevated position but the slides are now depressed to the position shown by dotted lines in Fig. 3, so as to bring the axial points of the hinges into line with the points of the quills. At 25 the same time, the slides 43 are operated so as to depress the spring hooks 42 and cause the ends of the same to pass between and project slightly inward beyond the points of certain of the quills, as shown by dotted 30 lines in Fig. 5. The segment 3^a is then unlocked from the ring 1 and said segment is swung around to the position shown in Fig. 2, so as to bring the point of each of the quills 10^a into contact with the point of its 35 corresponding quill 10, or by making one set of quills somewhat longer than the other set and slightly out of line therewith, the points of the quills may be caused to overlap when the parts are adjusted to the position shown 40 in Fig. 2. The result of this movement of the segment 3^a is to cause one-half of the tubular knitted web to be folded over upon the other half, each stitch around the edge of the folded portion of the web being now 45 in line with its corresponding stitch around the edge of the other half of the web. The retaining hooks 42 and 42^a are now withdrawn, and the segment 24^a is projected so as to cause its fingers 26^a to strip the stitches 50 from the quills 10^a and apply them to the quills 10, the segment 24^a being then retracted and the ring segment 3^a restored to its former position and again locked to the ring 1. The quills 10 can now be applied to the 55 stitch-receiving "points" of one-half of an ordinary circular looping machine and the stitches can be transferred from the quills to said points, either simultaneously, by the action thereupon of the fingers 26 of the segment 24 when the latter is moved downward, or the stitches can be pushed from the quills 10 onto the looper points by hand, in which case the use of the movable segment 24 in connection with the ring segment 3 will not 60 be necessary. The projection and retraction 65

of the segments 24 and 24^a are effected by hand, the maintenance of these segments in their normal or retracted position being due to the frictional hold of the same upon the parts adjacent thereto.

To permit of the folding of one portion of the web over upon the other, it is necessary that the stitches at and near the pivotal axis of the segments 3 and 3^a shall be close to the points of the quills 10 and 10^a, when the segment 3^a is swung from the position shown in Fig. 1 to that shown in Fig. 2, in order that there may be no lateral strain upon the stitches, as there would be if they occupied 70 positions more or less remote from the points of the quills. Before swinging the segment 3^a, therefore, the stitches at and near the pivotal axes of the hinges are moved down close to the points of the quills and the function 75 of the spring hooks 42 is to prevent their release from the points of the quills at such time.

My invention provides a convenient and effective means for performing an operation 80 which is now performed by hand and which requires the employment of skilled labor and is therefore expensive.

Many modifications of structural detail within the scope of my invention may also be devised by those skilled in the art and my 85 broader claims are drawn with the view of covering such modifications.

I claim:

1. In a machine of the character described, the combination of two sets of 90 stitch-receiving quills and supporting means therefor, adjustable to cause the quills of both sets to point in the same direction or the quills of one set to point toward the quills of the other set.

2. In a machine of the character described, the combination of two sets of 95 stitch-receiving quills and supporting devices therefor, provided with a pivotal connection whereby the quills of both sets may be caused to point in the same direction or one set of quills may be caused to point toward the other set.

3. In a machine of the character described, the combination of two sets of 100 stitch-receiving quills and supporting devices therefor, provided with a pivotal connection whereby the quills of both sets may be caused to point in the same direction or one set of quills may be caused to point toward the other set, said pivotal connection having its axis between the end quills of the two sets and adjacent to the points of the same.

4. In a machine of the character described, the combination of two sets of 105 stitch-receiving quills and supporting devices therefor, adjustable so as to cause the quills of both sets to point in the same direction or those of one set to point toward those 110

of the other set, and means for transferring stitches from one set of quills to the other when they are in the latter position.

5. In a machine of the character described, the combination of two sets of stitch-receiving quills, supporting devices therefor, adjustable so as to cause the quills of both sets to point in the same direction or those of one set to point toward those of the other set, and means for moving the quills in a direction transversely to their length.

6. In a machine of the character described, the combination of two sets of stitch-receiving quills, supporting devices therefor, adjustable so as to cause the quills of both sets to point in the same direction or those of one set to point toward those of the other set, means for moving the quills in a direction transversely to their length, and means for transferring stitches from one set of quills to the other when they are pointing toward each other.

7. In a machine of the character described, the combination of two sets of stitch-receiving quills, means for supporting the same, and a pivotal connection whereby both sets of quills may be caused to point in the same direction or one set may be caused to point toward the other set, said pivotal connection being movable into and out of line with the points of the quills.

8. In a machine of the character described, the combination of two sets of stitch-receiving quills, means for supporting the same, a pivotal connection whereby both sets of quills may be caused to point in the same direction or one set may be caused to point toward the other set, said pivotal connection being movable into and out of line with the points of the quills, and means for locking it in either of its positions of adjustment.

9. In a machine of the character described, the combination of two sets of stitch-receiving quills, supports therefor provided with pivotal connection, whereby both sets of quills may be caused to point in the same direction or those of one set may be caused to point toward those of the other set, a carrier for said quill supports, and means for locking the quill supports to said carrier.

10. In a machine of the character described, the combination of two sets of stitch-receiving quills, supports therefor provided with pivotal connection, whereby both sets of quills may be caused to point in the same direction or those of one set may be caused to point toward those of the other set, a carrier for said quill supports, and means for locking the quill supports to said carrier, one of said locking devices being releasable.

11. In a machine of the character de-

scribed, the combination of two sets of stitch-receiving quills, supports therefor having pivotal connection, whereby both sets of quills may be caused to point in the same direction or the quills of one set may be caused to point toward those of the other set, and slides mounted on said supports and carrying said pivotal connection.

12. In a machine of the character described, the combination of two sets of stitch-receiving quills, supports therefor having pivotal connection whereby both sets of quills may be caused to point in the same direction or the quills of one set may be caused to point toward the quills of the other set, and retainers whereby the stitches are prevented from escaping from the points of the quills while their relation to one another is being changed.

13. In a machine of the character described, the combination of two sets of stitch-receiving quills, supports therefor having pivotal connection whereby both sets of quills may be caused to point in the same direction or the quills of one set may be caused to point toward the quills of the other set, retainers whereby the stitches are prevented from escaping from the points of the quills while their relation to one another is being changed, and means for adjusting said retainers to operative or inoperative position.

14. In a machine of the character described, the combination of two sets of stitch-receiving quills, supports therefor having a pivotal connection whereby the quills may be adjusted so that both sets point in the same direction or the quills of one set point toward those of the other set, and retainers for preventing escape of the stitches from the quills while their relation to one another is being changed, certain of said retainers being coincident with the pivotal axes of the quill supports.

15. In a machine of the character described, the combination of two sets of stitch-receiving quills, adjustable supports therefor whereby both sets of quills may be caused to point in the same direction or the quills of one set may be caused to point toward those of the other set, and means for stripping the stitches from a set of quills.

16. In a device of the character described, the combination of two sets of stitch-receiving quills, supports therefor adjustable so as to cause both sets of quills to point in the same direction and the quills of one set to point toward those of the other set, and means for transferring the stitches from the quills of one set to those of the other set.

17. In a device of the character described, the combination of two sets of stitch-receiving quills, adjustable supports therefor, whereby both sets of quills may be caused

to point in the same direction or the quills of one set may be caused to point toward those of the other set, spring hooks serving to retain the stitches upon the quills, and means for acting upon said spring hooks to project the same into retaining position.

18. In a device of the character described, the combination of two sets of pivoted quills each having a beveled lug thereon, supports 10 for said quills adjustable so as to cause both sets of quills to point in the same direction or the quills of one set to point toward those of the other set, and means for acting upon the beveled lugs of the quills to cause 15 said quills to swing in a direction transverse to their length.

19. In a device of the character described, the combination of two sets of pivoted quills each having a beveled lug thereon, supports 20 for said quills adjustable so as to cause both sets of quills to point in the same direction or the quills of one set to point toward those of the other set, means for acting upon the beveled lugs of the quills to cause said quills 25 to swing in a direction transverse to their length, and elastic means for restoring the quills to their normal position.

20. In a machine of the character described, the combination of two semi-circular sets of stitch-receiving quills and supporting segments therefor, adjustable to cause the quills of both sets to point in the same direction or the quills of one set to point toward the quills of the other set.

21. In a machine of the character described, the combination of two semi-circular sets of stitch-receiving quills and supporting segments therefor, provided with 35 pivotal connections whereby the quills of both sets may be caused to point in the same direction or one set of quills may be caused to point toward the other set.

22. In a machine of the character described, the combination of two semi-circular sets of stitch-receiving quills and supporting segments therefor, provided with 45 pivotal connections whereby the quills of both sets may be caused to point in the same direction or one set of quills may be caused to point toward the other set, said pivotal connections having their axes between the end quills of the two sets and adjacent to the points of the same.

23. In a machine of the character described, the combination of two semi-circular sets of stitch-receiving quills and supporting segments therefor, adjustable so as to cause the quills of both sets to point in the same direction or those of one set to point toward those of the other set, and means for transferring stitches from one set of quills to the other when they are in the latter position.

24. In a machine of the character described, the combination of two semi-circu-

lar sets of stitch-receiving quills, supporting segments therefor, adjustable so as to cause the quills of both sets to point in the same direction or those of one set to point toward those of the other set, and means for moving the quills in a direction transversely to their length.

25. In a machine of the character described, the combination of two semi-circular sets of stitch-receiving quills, supporting 75 segments therefor, adjustable so as to cause the quills of both sets to point in the same direction or those of one set to point toward those of the other set, means for moving the quills in a direction transversely to their length, and means for transferring stitches of one set of quills to the other when they are pointing toward each other.

26. In a machine of the character described, the combination of two semi-circular sets of stitch-receiving quills, segments 80 for supporting the same, and pivotal connections whereby both sets of quills may be caused to point in the same direction or one set may be caused to point toward the other set, said pivotal connections being movable 85 into and out of line with the points of the quills.

27. In a machine of the character described, the combination of two semi-circular sets of stitch-receiving quills, segments 90 for supporting the same, pivotal connections whereby both sets of quills may be caused to point in the same direction or one set may be caused to point toward the other set, said pivotal connections being 95 movable into and out of line with the points of the quills, and means for locking them in either of their positions of adjustment.

28. In a machine of the character described, the combination of two semi-circular sets of stitch-receiving quills, segmental supports therefor provided with pivotal 100 connections, whereby both sets of quills may be caused to point in the same direction or those of one set may be caused to point toward those of the other set, a ring carrying 105 said quill-supporting segments, and means for locking said segments to said ring.

29. In a machine of the character described, the combination of two semi-circular sets of stitch-receiving quills, segmental supports therefor provided with pivotal 110 connections, whereby both sets of quills may be caused to point in the same direction or those of one set may be caused to point toward those of the other set, a ring carrying 115 said quill-supporting segments, and means for locking the segments to said ring, one of said locking devices being releasable.

30. In a machine of the character described, the combination of two semi-circular sets of stitch-receiving quills, seg- 120

mental supports therefor having pivotal connections, whereby both sets of quills may be caused to point in the same direction or the quills of one set may be caused to point 5 toward those of the other set, and slides mounted on said segments and carrying said pivotal connections.

31. In a machine of the character described, the combination of two semi-circular sets of stitch-receiving quills, segmental supports therefor having pivotal connections whereby both sets of quills may be caused to point in the same direction or the quills of one set may be caused to point 10 toward the quills of the other set, and retainers whereby the stitches are prevented from escaping from the points of the quills while their relation to one another is being changed.

32. In a machine of the character described, the combination of two semi-circular sets of stitch-receiving quills, segmental supports therefor having pivotal connections whereby both sets of quills may be caused to point in the same direction or the quills of one set may be caused to point 15 toward the quills of the other set, retainers whereby the stitches are prevented from escaping from the points of the quills while 20 their relation to one another is being changed, and means for adjusting said retainers to operative or inoperative position.

33. In a machine of the character described, the combination of two semi-circular sets of stitch-receiving quills, segmental supports therefor having pivotal connections whereby the quills may be adjusted so that both sets point in the same direction or the quills of one set point toward those 35 of the other set, and retainers for preventing escape of the stitches from the quills while their relation to one another is being changed, certain of said retainers being coincident with the pivotal axes of the quill 40 supporting segments.

34. In a machine of the character described, the combination of two semi-circular sets of stitch-receiving quills, adjustable segmental supports therefor whereby 45 both sets of quills may be caused to point in the same direction or the quills of one set may be caused to point toward those

of the other set, and means for stripping the stitches from a set of quills.

35. In a device of the character described, 55 the combination of two semi-circular sets of stitch-receiving quills, segmental supports therefor adjustable so as to cause both sets of quills to point in the same direction and the quills of one set to point 60 toward those of the other set, and means for transferring the stitches from the quills of one set to those of the other set.

36. In a device of the character described, 65 the combination of two semi-circular sets of stitch-receiving quills, adjustable segmental supports therefor, whereby both sets of quills may be caused to point in the same direction or the quills of one set may be caused to point toward those of the other 70 set, spring hooks serving to retain the stitches upon the quills, and means acting upon said spring hooks to project the same into retaining position.

37. In a device of the character described, 75 the combination of two semi-circular sets of pivoted quills each having a beveled lug thereon, segmental supports for said quills adjustable so as to cause both sets of quills to point in the same direction or the quills 80 of one set to point toward those of the other set, and means for acting upon the beveled lugs of the quills to cause said quills to swing in a direction transverse to their 85 length.

38. In a device of the character described, the combination of two semi-circular sets of pivoted quills each having a beveled lug thereon, segmental supports for said quills adjustable so as to cause both sets of quills 90 to point in the same direction or the quills of one set to point toward those of the other set, means for acting upon the beveled lugs of the quills to cause said quills to swing in a direction transverse to their 95 length, and elastic means for restoring the quills to their normal position.

In testimony whereof I have signed my name to this specification, in the presence of two subscribing witnesses.

WALTER D. BUTZ.
